(57) **CLAIM**

The ornamental design for a mouse pad, as shown and described.

DESCRIPTION

FIG. 1 is a top perspective view of a mouse pad showing my new design.

FIG. 2 is a top view thereof.

FIG. 3 is a bottom view thereof.

FIG. 4 is a right side view thereof.

FIG. 5 is a left side view thereof.

FIG. 6 is a front side view thereof; and,

FIG. 7 is a back side view thereof.

The broken lines that define the bounds of the claimed design form no part thereof.

A mouse pad for computer mice.
